UNITED STATES PATENT OFFICE.

LINDSAY H. CRAWFORD, OF CHICAGO, ILLINOIS.

UNDERGARMENT.

1,140,122.

Specification of Letters Patent. Patented May 18, 1915.

Application filed November 6, 1914. Serial No. 370,578.

To all whom it may concern:

Be it known that I, LINDSAY H. CRAWFORD, a citizen of the United States, residing at Chicago, in the county of Cook and State 5 of Illinois, have invented certain new and useful Improvements in Undergarments, of which the following is a full, clear, and exact description, such as will enable others skilled in the art to which it appertains to 10 make and use the same.

This invention relates to garments, and with respect to its more specific features, to union garments of underwear.

One of the objects of this invention is the 15 provision of a practical lined union garment of underwear.

Another object is the provision of an efficient lined union undergarment adapted to be worn next the skin, and which will avoid, 20 in a great measure, the tight or constricted feeling of such garments attendant upon certain conditions of wear.

Another object of the invention is the provision of an inexpensive union under- 25 garment of increased warmth giving qualities, and a comfortable "feel" under adverse conditions of use.

The invention accordingly consists in the features of construction, combinations of 30 elements and arrangement of parts which will be exemplified in the construction hereinafter set forth, and the scope of the application of which will be indicated in the following claims.

35 In the accompanying drawings, forming a part of this specification, and wherein similar reference characters refer to similar parts throughout the several views: Fig. 1 illustrates one form of the invention in front 40 view, with the front of the garment thrown back to more clearly disclose the invention; Fig. 2 is a rear view of the garment shown in Fig. 1, the front being closed; Fig. 3 is a view showing the garment on a person 45 seated, the garment being partly sectioned for clearer disclosure; and Fig. 4 is a view showing the garment on a person in a bent or bowed position, and in which the outer body fabric is broken away to show the inner lining.

Referring now more specifically to the drawings, the numeral 1 indicates a union suit or union garment which is intended to be worn next to the skin. It comprises a 55 body portion 2, leg portions 3, 3 and arm portions 4, 4, which latter may be of the

sleeve form or armlets, as desired. The legs are connected to the body portion, either being formed integrally therewith, or otherwise. In the ordinary position of a union 60 garment on the wearer, it extends from the shoulders to the knees or below the knees, and also between the legs. In the posterior of the garment a utility opening is provided, the same consisting of a slit 5, extending 65 upwardly in the rear, from the crotch region a sufficient distance to afford a proper sized opening when the edges of the slit are transversely spaced from each other. In the embodiment disclosed, the slit 5 extends to the 70 waistline, or above, as at 6, its upper end terminating below the upper edge of the body portion. In the present embodiment the lower extremity of the slit is separated 75 from the lower extremity of the front but- toning opening 7 by an intervening portion 8 of the material of the garment, so that the posterior slit is not continuous with the front opening, although the advantages of the invention manifest themselves even 80 though the front and rear openings of the garment are continuous. When the union garment above described is on the person, the portion 8, or the part of the garment adjacent the lower extremity of the slit 7 85 underlies the trunk of the person. When the wearer is standing this garment fits the body nicely, and sufficient looseness of fit at the crotch may be provided so that in this position little or no upward pressure at the 90 crotch of person will result, but when the wearer bends over, and especially forwardly, as when in a sitting position, there is produced a longitudinal tension of the garment which is especially marked at the loin and 95 buttock portions of the garment, the fabric stretching somewhat tightly around these parts longitudinally of the body, and also transversely, which results in the garment being drawn longitudinally toward the per- 100 son at that part between the legs, and undue, uncomfortable and injurious pressure and friction may be produced on these more delicate parts. The production of this pressure is especially noticeable when the person 105 is bending forwardly, as when seated, and is covered with moisture, as perspiration. Under such circumstances the garment is, as it were, gripped between the person and the chair seat, or between the person and the 110 outer clothing, which latter will be tight around the hips and over the buttocks, so

that the extent to which the body portion of the garment may stretch longitudinally is diminished, as in this situation the full length of the garment is not unrestrained, 5 the intermediate portion being practically held between the chair and the person or between the outer clothing and the person, so that the free elongation of only that part above the seat of the chair is freely available 10 for the upper portion of the person. The present improvement facilitates the stretching of a union undergarment, both longitudinally and transversely, increases its warmth-giving qualities, in a great measure 15 does away with any uncomfortable tight feeling of union undergarments, and adds to their wearing qualities.

The numeral 9 indicates a ply of fabric, which ply lies on inside of the body portion 20 of the union garment, and, from one aspect of the invention, serves as a lining, to give additional warmth to the parts covered thereby. In the present embodiment this inner ply or lining 9 is secured to the body portion of the garment in a loose manner 25 to permit the lining and the body portion to move or "play" relatively to each other, this object being attained, in the present instance, by attaching the lining to the garment at different parts, the lining lying loosely on the garment for a greater portion 30 of its extent between its edges. In the form illustrated, the lining is secured to the garment by a series of stitches on a line transversely disposed relative to the garment, and also by stitches forming seams longitudinally of the garment. The transversely disposed stitches are preferably comprised 35 in a seam 10, formed at the upper edge of the lining 9 and attaching the lining to the posterior of the body portion, the stitches being somewhat loosely assembled with the material so as to be capable of extension transversely of the garment. In the preferred form both the body of the garment 40 and the lining are composed of elastic fabric, preferably a knitted fabric, the wales of each of which are disposed longitudinally of the garment, the lining fabric being of finer mesh than that of the body fabric so as to offer a softer "touch," and also to permit the body to more readily 45 move longitudinally relatively to the lining. The extensible seam 10, formed as described, permits the body and the lining to extend and contract transversely of the garment, the seam referred to not materially interfering with these operations. The lining 50 is preferably substantially coextensive with the circumference of the garment on the inside from the upper portion of the lining where is located the seam 10 down to the upper extremity 6 of the posterior slit 5, the longitudinal sides of the lining being secured to the garment adjacent the edges of 55

the front opening 7, as at 11, and being finished off by binding, as 12. The lining also extends below the upper extremity of the slit 5, and portions of the lining or ply 9 lie on either side of said slit. The lower 60 edge 13 of the lining lies free upon the inner face of the outer, or garment, fabric, for a substantial distance transversely of the garment, the free portions in the present embodiment being comprised between the 65 lower ends of the seams 14, 14 and the edges of the front opening, respectively, this latter opening extending from the neck of the garment to the part 8 and being provided with buttons and buttonholes, as usual. In 70 the preferred construction the lining extends downwardly from the transverse seam 10 into the buttock portion of the garment and terminates in the lower edge referred to, said lower edge being in substantially 75 the horizontal plane of the crotch region.

On the opposite sides of the slit 5 the lining is secured or seamed generally longitudinally to the edges of the slit, as at 14, 14, 80 and the garment fabric at one side of the slit 5 is extended transversely beyond the lining fabric on that side so as to be adapted to overlie the garment fabric on the other side of said slit, forming a flap, as indicated 85 at 15. The opposite side of the slit may also have an extended portion or flap, as indicated at 16. Obviously these flap extensions 15 and 16 may be made integral with the garment fabric or, as illustrated, by 90 pieces seamed thereto on lines identical with the seams 14, 14. Opposite the slit 5, there is an opening or slit 17 in the lining, and in the form illustrated it will be observed that the lining fabric on either side of the garment slit 5 is provided by portions of lining 90 lying on either side of the lining slit 17 extending from the lower edge of the lining, the portion of the lining above the slit 5 being 100 preferably continuous both transversely and longitudinally. By thus slitting or dividing the lining, there will be no flap or lining lying across the posterior slit 5, which flap, if provided, would have to be lifted or otherwise disposed of when using the 105 posterior slit 5. A considerable extent of the inner ply, or lining 9, lies loosely upon the garment fabric, in the form illustrated the lining being connected to the garment fabric mainly at its edges, as at the sides 110 of the front opening and at the edges of the posterior slit, as before described.

The garment is designed to be worn next the skin beneath the outer clothing, and when the person of the wearer is covered with perspiration the lining will at times stick to the person, but by reason of the looseness thereof relative to the outer or garment fabric, the latter fabric is permitted 115 to move upwardly or to stretch or elongate 120

longitudinally, notwithstanding the fact that portions of the lining may adhere to the person of the wearer. When the person is seated, or in a bended posture, as illustrated in Figs. 3 and 4, the amount of tension on elongation of the garment fabric is measured inversely by the longitudinal extent of that portion of the fabric which is permitted to extend longitudinally, and it will be noted that should the lining be not present, the lower portion of the body fabric, that is, that portion in the general plane of the longitudinally curved portion of the seated person, as at the buttock portion, as at 18, would stick or adhere to the person and resist elongation, so that most of the elongation would take place in the upper part of the garment fabric, where, by reason of less degree of curvature of the person, the adherence was not so strong. By providing the lining, however, there is furnished a surface less dense in moisture than the person, and it is against this surface that the garment fabric lies, and it may more readily move over this lining surface, so that when assuming a seated position a greater longitudinal extent of the garment may be availed of for elongation, and thus, when the person is seated, the longitudinal tension of the garment fabric will not be so great. Furthermore, the transverse elasticity of the lining is availed of under such circumstances, as the extensible and contractile seam 10 referred to, permits the garment fabric, for instance a portion 19 adjacent the transverse seam, to stretch longitudinally of the garment and pull a portion of the lining with it, even though the remainder of the lining continues to adhere to the person. Thus the effect will be to draw that portion of the lining in a resultant longitudinal direction of the extension of the body fabric, the transverse elasticity of the lining fabric permitting the lining to extend freely transversely so as to offer material to be drawn by the body portion, even though an adjacent portion of the lining be adhering to the person. Though the lining fabric be seamed to the opposite sides of the posterior slit, as at 14, 14, the condition of relative movement of the lining fabric and body fabric is still maintained, as the edges of the garment adjacent the slit provide relatively freely movable portions which may be drawn upwardly or transversely and thus will not be a substantial restraint to the relative movement referred to.

In order to emphasize the special utility of the lining 9, in facilitating the extension of the garment, especially the longitudinal extension, the lining 9, in Figs. 3 and 4, is shown as disposed around the curve of the buttocks up to the rear end of the part 8, thereby providing a fullness of the lining 65 comporting with that of that portion of the

garment inclosing the buttocks. It will be seen that the greatest degree of longitudinal curvature of the person is around the buttock portion, as between the points *a* and *b*, and that from the point *a* upwardly and the point *b* downwardly the garment extends in a gentle curve, so that its tendency to stick to the person above the point *a* and below the point *b* is not so great as that between the points *a* and *b*. Hence below the point *b* and above the point *a*, the garment may elongate more readily than between said points. But the sticking of the garment to the person between the points *a* and *b* in a great measure confines the elongation of the garment to separate parts, the body portion elongating from the point *a* upwardly, and the leg portion from the point *b* toward the knees. By providing the lining, between the points *a* and *b*, a surface is provided which will permit the body portion of the outer fabric to utilize elongation possible in the leg portions, the outer fabric sliding more readily over the lining than over the damp or wet skin.

While the invention is disclosed in connection with an inner ply which terminates below the upper edge of the garment, it is of course to be understood that the form shown is merely illustrative, and that the utility of the invention is preserved even though the inner ply extend to the upper edge of the garment. For instance, it might extend to the edge of the shoulder insert 21, which latter is of knitted fabric with the wales running transversely of the garment. It is also to be understood that the disclosed location of the transversely extensible seam is merely illustrative and that the invention is not detracted from by employing a plurality of such seams similarly disposed to coöperate in the manner related.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense. It is also to be understood that the language used in the following claims is intended to cover all of the generic and specific features of the invention herein described, and all statements of the scope of the invention which, as a matter of language, might be said to fall therebetween.

Having described my invention, what I claim as new and desire to secure by Letters Patent is:

1. A union garment of underwear comprising, in combination, a body portion and leg portions connected thereto, said garment having a posterior opening extending upwardly from the crotch region, and a lining

- lying loosely on the body portion, extending to approximately the horizontal plane of the crotch region and secured in part to the body portion by an extensible seam disposed transversely of the garment.
2. A union garment of underwear comprising, in combination, a body portion of elastic fabric and leg portions connected thereto, said garment having a posterior opening extending upwardly from the crotch region, and a lining of elastic fabric lying loosely on the body portion and secured in part thereto by an extensible seam disposed transversely of the garment.
- 15 3. A union garment of underwear comprising, in combination, a body portion of elastic fabric and leg portions connected thereto, said garment having a posterior opening extending upwardly from the crotch region, and a lining of elastic fabric comprising portions lying on the inside of the body portion and secured adjacent opposite sides of said opening, said lining lying loosely on the body portion and secured in part thereto by an extensible seam disposed transversely of the garment.
- 20 4. A union garment of underwear comprising, in combination, a body portion of knitted fabric having the wales disposed longitudinally of the garment and leg portions connected to said body portion, said garment having a posterior opening extending upwardly from the crotch region, and a lining of knitted fabric of finer mesh than the mesh of the body portion lying on the inside of the body portion and secured thereto at opposite sides of said opening, the wales of the lining fabric being disposed longitudinally of the garment, said lining
- 25 40 lying loosely on the body portion and secured in part thereto by an extensible seam

permitting both the lining and the body portion to extend and contract transversely of the garment.

5. A union garment of underwear comprising, in combination, a body portion and leg portions connected thereto, said garment having a posterior slit extending upwardly from the crotch region, and an elastic fabric lining lying on the inside of the body portion and attached thereto by an extensible and contractile seam lying transversely of the garment, said lining lying on the garment below said seam and extending to substantially the horizontal plane of the crotch region and adapted to play on said garment adjacent said seam, the lower transversely disposed edge of said lining being, at places, unsecured to said garment.

6. A union garment of underwear comprising, in combination, a knitted fabric body portion and leg portions, said garment having a posterior slit extending upwardly from the crotch region, the wales of said fabric being disposed longitudinally of the garment, and a knitted fabric lining lying on the inside of the body portion and at opposite sides of said slit, the wales of the lining fabric being disposed longitudinally of the garment, said lining being attached to the body portion by a line of stitches disposed transversely of the body portion, said stitches being so arranged as to permit both the lining and the body portion to extend and contract transversely of the garment.

In testimony whereof I affix my signature, in the presence of two witnesses.

LINDSAY H. CRAWFORD.
